CLAIM

The ornamental design for an electrical pin connector, as shown and described.

DESCRIPTION

FIG. 1 is top front and right side perspective view of an electrical pin in showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan side view thereof.

The broken lines shown in the drawing views represent unclaimed environmental structure only and form no part of the claimed design.
